UNITED STATES PATENT OFFICE.

MICHAEL B. GREEN, OF MEMPHIS, TENNESSEE.

OIL-PRESS.

1,252,342.

Specification of Letters Patent.

Patented Jan. 1, 1918.

Application filed June 20, 1917. Serial No. 175,949.

To all whom it may concern:

Be it known that I, MICHAEL B. GREEN, a citizen of the United States, residing at Memphis, in the county of Shelby and State 5 of Tennessee, have invented new and useful Improvements in Oil-Presses, of which the following is a specification.

This invention relates to oil presses and it consists in the novel features hereinafter 10 described and claimed.

An object of the invention is to provide an improved structure over those shown in my earlier Patents No. 1,061,837, issued May 13, 1913, and 1,081,905, issued December 16, 15 1913, and over the structure shown in my pending application Ser. No. 88,903.

In the present structure the press comprises top and bottom blocks connected together by means of bolts in the usual manner and provided with a plunger or follower 20 adapted to be actuated by liquid in the usual manner. Columns are connected at their ends with the top and bottom blocks and compression bars are provided with guides 25 adapted to move along the said columns. Some of the said bars are provided at their upper sides with flanges having recesses adapted to receive hair mats and drain perforations or openings pass through the 30 said flanges and communicate with the said recesses. The said bars are arranged in sets and plates are slidably mounted with relation to each set of bars. Lever mechanisms are operatively connected with some of the 35 upper plates and also operatively connected with the lower plate whereby the said lower plate may be moved in an upward direction at a faster rate of speed than the upper plate in consequence of being subjected to pressure 40 from the plunger. The bars are provided with suitable grooves whereby the oil which is squeezed from the material located between the sets of bars may drain and drip upon the upper surface of the plunger.

45 In the accompanying drawings:—

Figure 1 is an end elevation of the press with parts in section showing the plunger in its lowest position;

Fig. 2 is a similar view showing the plunger in an elevated position;

Fig. 3 is a fragmentary side elevation of the press viewing the same at a right angle to the illustration shown in Fig. 1;

Fig. 4 is a fragmentary horizontal sectional view of the press cut on the line 4—4 of Fig. 1;

Fig. 5 is a detailed sectional view through the intermediate portion of a set of bars used in the press.

The press comprises a top or head block 1 60 and a bottom block 2 connected together by means of bolts 3 in the usual manner. A plunger 4 is movably mounted above the bottom block 2 and may be actuated by oil or any suitable liquid under pressure in the 65 usual manner. Columns 5 are secured at their ends to the top and bottom blocks. Bars 6 are arranged in sets and the outer bars of each set are provided at their edges with guides 7 which slidably receive the columns 5. The bars 6 are provided with grooves 8 whereby the liquid which is 70 squeezed from the material placed between the sets of bars may drain from the same. A filler 10 is mounted at the lower surface of 75 the top or head block 1 and is adapted to cooperate with the upper set of bars 6.

The outer bars 6 of each set are provided at their upper sides with flanges 11 having recesses 9 adapted to receive hair mats 12. 80 The flanges are further provided with openings 13 which communicate at their inner ends with the recesses 9 and serve as means whereby the oil or liquid may drain from 85 between the sets of bars.

Hangers 15 are provided at their upper ends with slots 16 which receive bolts 17 attached to the edges of the top or head block 1. The said hangers are attached at their lower ends to the outer bars 6 of the 90 upper set of bars.

Plates 20 are slidably mounted at the ends of each set of bars 6. The said plates are provided with flanges 21 having slots 22 which receive pins 23 carried by the outer 95 bars 6 of each set of bars except the lowest set. The plates 20 except the lowest plates are provided with legs 24 and the legs of the upper plates are attached to the outer bars 6 of the next lower set of bars. The plates 20 are further provided with openings 25. The legs of the plates 20 adjacent the ends of the third set of bars 6 from the bottom of the press are provided with extensions 26 which are pivoted to the outer 100 ends of levers 27 fulcrumed at the ends of the outer bars 6 of the lowest set of bars. The inner ends of the levers 27 are pivoted to the end portions of the lowest plate 20.

As illustrated in Figs. 1 and 2, the pivotal 110 connections between the levers 27 and the lowest plate 20 and the leg extensions 26 are

of pin and slot structure in order that the parts may have proper movement with relation to each other when the press is in operation.

5 In operation the material to be pressed is placed between the adjacent sets of bars 6 and the plunger 4 is caused to move in an upward direction whereby the lower boxes approach the upper boxes successively as the 10 weight or support of the boxes and meal or contents is transferred from the pins 23 to a pressure on the lower box or plunger. This process continues until all of the weight 15 of the boxes and contents has been removed from the pins 17 at which time the continuation of the rise of the plunger 4 takes up the weight of the head block and then puts tension in the bolts 3. It is during the movement of the plunger 4 before the entire 20 weight is removed from the pins 17 that the chief and important motion of the end plates 20 takes place. This pressure causes the oil to ooze from the said material and the oil drains from the bars through the grooves 8 25 and the openings 13 and runs down into the upper portion of the plunger 4 in the usual manner. As the lowest set of bars 6 of the series of sets is forced up closer toward the next set above the leg extensions 26 cause 30 the levers 27 to swing on their pivotal connection with the bars whereby the lowest plates 20 are moved in an upward direction at a faster rate of speed than the upper plates 20 and this confines the material between the two lower sets of bars and effectually squeezes or presses all of the oil out of the same.

From the foregoing description taken in conjunction with the accompanying drawing, 40 it will be seen that an oil press of simple and durable structure is provided and that the same may be used economically to advantage for squeezing the oil from material, as for instance, cotton seed and that

the said oil is permitted to drain from the 45 bars into the plunger where it is collected and may be removed from the same at desired intervals.

Having described the invention what is 50 claimed is:—

1. A press comprising top and bottom blocks, suitably connected together, a plunger movably mounted between the blocks, sets of bars located between the blocks, the outer bars of the sets being provided with 55 flanges having at their inner sides recesses and provided with openings passing transversely through the flanges and communicating with the said recesses.

2. A press comprising top and bottom 60 blocks suitably connected together, a plunger mounted for movement between the said blocks, sets of bars movably mounted between the blocks, the outer bars of the sets being provided with flanges having at their 65 inner portions recesses and provided with openings which communicate at their inner ends with the said recesses and mats located in said recesses.

3. A press comprising a frame, a plunger 70 movably mounted thereon, sets of bars movably mounted on the frame, plates movably mounted at the ends of each set of bars, levers fulcrumed upon the outer bars of the lower set and operatively connected with 75 the lowest plate, some of the upper plates having leg extension connected with the outer ends of said levers.

4. A press comprising a frame, a plunger 80 movably mounted thereon, sets of bars movably mounted on the frame, plates movably mounted at the ends of each set of bars, the upper plates being provided at their ends with legs which are attached to the outer 85 bars of the next adjacent lower sets of bars.

In testimony whereof I affix my signature.

MICHAEL B. GREEN.
